UNITED STATES PATENT OFFICE.

HUGO REICHEL AND WILLIAM L. NIES, OF CHICAGO, ILLINOIS.

ICE-CREAM CUTTER.

Application filed April 5, 1922. Serial No. 549,788.

To all whom it may concern:

Be it known that we, HUGO REICHEL and WILLIAM L. NIES, being citizens of the United States, and residents of Chicago, in the county of Cook and State of Illinois, and whose post-office address is 452-456 North Ashland Avenue, Chicago, Illinois, have invented a certain new and useful Improvement in Ice-Cream Cutters, of which

10 the following is a specification.

Our invention relates to an apparatus for cutting blocks of plastic material, and is particularly applicable to the separation of butter or ice cream into a large number of 15 small blocks or squares. It has for one object to provide means for reducing a large block of ice cream or similar plastic material, by one operation, into a large number of blocks of the proper size to pack and sell. It has for a further object to provide 20 a machine of the type above described which shall be particularly adaptable for quick operation, and which shall avoid complicated parts and be simple and easy to manufacture and operate. Other objects will appear from time to time in the course of the 25 specification.

We illustrate our invention more or less diagrammatically in the accompanying 30 drawings, wherein—

Figure 1 is a plan view;

Figure 2 is a side elevation with parts broken away;

Figure 3 is an end view;

Figure 4 is a section on the line 4—4 of Fig. 2;

Figure 5 is a section on the line 5—5 of Figure 1.

Like parts are represented by like letters and numbers throughout the drawings.

A is a supporting base of any suitable form, which is provided with a flat upper surface or surfaces A'. Upwardly projecting from one side thereof are the supports A² A², from which projects laterally a transverse element A³ spaced substantially above the surface A' but overhanging it, and terminating in a plurality of perpendicular bearing elements A⁴ which are faced with wood blocks A⁵ and are separated by the pockets A⁶ having narrow vertical mouths A⁷.

At both ends of the base are the upwardly projecting supporting posts B B' providing the similar rectangular openings B² to per-

mit the passage therethrough of the material to be cut. The upper inner surfaces are rabbeted as at B³ B³ to provide guide ways adapted to receive the ends C² C³ of the knife supporting element C⁴ which is provided with a central, vertically, projecting, reinforcing rib C⁵. The knife supporting element C⁴ is retained in the guide ways by the guide plates B⁴ B⁴.

Projecting from the ends C² C³ are the lugs D D' to which are secured the racks D² D³, which are supported on pinions D⁴ D⁵ keyed to the driving shaft D⁶, which is rotatably mounted in any suitable manner, as, for example, in the end posts B B'. The racks may be kept in position against the pinions, as, for example, by the overhanging lugs D⁹ D¹⁰. The pinions are actuated either through the gear D'' keyed to the shaft D⁶, which may be connected with any suitable power source not shown or by the manual crank D¹² keyed to the end of the shaft.

The lower surface of C⁴ is broken by a series of flat bottom openings or slots E, one side, E' of each of which is perpendicular and the other side E² is inclined. Bolts E³ are screw-threaded to penetrate through the upper surface of C⁴ and into the slots, where they rotatably engage the wedge blocks E⁴, which have inclined sides E⁵ in opposition to the inclined sides E² of the slots, and vertical sides E⁶ in opposition to the vertical sides E' of the slots, the blocks being of smaller width than the inside of the slots.

The rotation of the bolts E³ serves to wedge the blocks against the inclined sides of the slot and against the knife blades F, which are inserted into the slots between the opposed vertical slot and block walls. These knife elements each comprise an inclined cutting or blade portion F' and a rear rounded portion F², the lowermost portion of the knife blade terminating at a point spaced substantially above the surface A'.

At the right end of the gang knife, as shown in Fig. 2, is a descending pin G, which is adapted to engage a lug G' on a slide or stop G² which is slidably mounted at the right end of the base, as shown in Figs. 1 and 2. This stop or slide is slotted, as at G³, to engage a bolt G⁴, and is provided with yielding means G⁵ adapted to return it to normal position when the gang knife has been withdrawn.

H is any suitable plate or support on which is laid a brick H' of the substance to be cut. The plate and brick are inserted from the left, as shown in Figs. 1 and 2, and 5 the plate is of such dimensions as just to clear the bottom of the knife elements, the blocks A⁴ and the slide or stop G².

It will be realized that while we have 10 shown and described an operative device, still many changes might be made in the size, shape, number and relation of parts without departing from the spirit of our invention. We wish, therefore that our 15 drawings be taken as in a sense diagrammatic.

The use and operation of our invention are as follows:

Heretofore it has been the custom to separate large blocks of ice cream into smaller 20 blocks by feeding the block forward into a cutting zone and cutting off slices from it one by one—that is to say, for each cut the block was fed forward to position for the succeeding cut. The present apparatus and 25 process provide for the simultaneous severing of the block into a number of pieces, and the apparatus permits of this process being carried on continuously, since the large blocks of ice cream are fed into the machine 30 at one end and are removed from it at the other. This has been illustrated as a largely manual process, but it is obvious that the bricks could be put on a mechanical carrier and carried through the cutting zone by a 35 step-by-step motion, the entire process thus being made mechanical and automatic.

We illustrate a cutter having a flat base, 40 on the flat upper surface of which may be placed any suitable block or board on which is laid the large brick from which the smaller bricks are to be cut. It will be understood that in prevailing practice ice cream is prepared in a large brick, possibly 45 as much as two feet in length. This brick may be loosened from the form in which it is frozen, as, for example, by heating the form with hot water, and the brick is then dropped upon a board or plate. This plate, with the brick in position thereon, is slid 50 over the flat base of the machine, being inserted from the left, as shown in Fig. 1, through the opening in the end wall. The brick is loose on the board, being kept in position thereon simply by frictional contact. The stop at the opposite end of the 55 machine limits the forward motion of the brick and when the brick is in position thereagainst the operator, who has manually inserted the board, will push it no farther. In inserting the board and brick he preferably sees that the right side of the 60 brick lies close to the series of stops shown at the bottom of Fig. 1. These stops, as shown in Fig. 3, clear the board, so the board may, if necessary, be shoved there-

under to position the brick, and the end stop also clears this board; and when the brick is thus positioned the operator is ready to perform the cutting operation. The gang 70 knife is in position as shown at the top of Fig. 1, and at the left of Fig. 3. The operator can either turn on the power, if he is using a power-driven machine, or he can turn the crank if he is using a manual machine, and the pinions connected thereto 75 mesh with the racks which are connected to either end of the gang knife. The knife is thus drawn across the machine and against the brick, the lower edges of the various knife elements just clearing the board. The 80 knives are drawn all the way across through the brick and into the receiving hollows between and behind the stops at the opposite side of the machine, in order entirely to 85 clear the path of the brick, for removal after the cutting.

A downwardly projecting stop or pin at the right end of the gang knife, as shown in Fig. 1, engages an outwardly projecting member on the stop and withdraws it, thus 90 further clearing the path for removal of the board and the cut brick, which may then be slid out of the machine at the opposite end. Any suitable means—for example, a 95 spring—may be provided for returning the end stop to position when the gang knives are withdrawn to the opposite side of the machine in readiness for the next cutting operation.

The various elements of the gang knife 100 are removable and adjustable by means of the wedge and nut shown in Fig. 5, the opposed inclined sides of the wedge and pocket serving to clamp the knife between the opposite opposed straight sides when the bolt 105 is rotated.

The simplicity and ease of use of this machine renders it an enormous improvement 110 of the machines of the past, and over unguided manual methods which are so frequently used. The bricks are fed forward into the machine and cut on the same board from which they are dropped from the slab moulds. The slab from which the bricks are 115 cut is automatically registered in relation to the knives, since it is necessary simply to push the board forward until the slab contacts the end stop. The knives themselves will push the slab against the side stops although the operator will generally move the board and brick in proper relation thereto. All the careful registry of slab and cutting 120 knives which is characteristic of earlier processes, is avoided and the slab may lie anywhere on the cutting board which of course, passes freely over the hanging side stop. The register stop disappears during the cut permitting a continuous process whereby the slab and the board may be 125 pushed forward out of the opposite end of 130

the machine. A large number of bricks may be cut at each stroke, although but few moving parts are used, the most important of which are the shaft and the knife carrying slide. The bricks may be cut without any manual handling of the slab or bricks. The knives are designed to give a shearing cut, thus eliminating tearing action when nuts and fruit are contacted. The knives are so mounted as to permit instant removal or replacement. The cut is made through the slab in one direction and the cut slab is pushed forward out of the way before the return stroke, thus eliminating tearing or shearing of the corners of the bricks cut from the slab. Since there are no delicate parts of the machine, it cannot get out of order, and it is easily kept clean and sanitary, it can be cleaned by mere hose flushing. While this machine has been described particularly in connection with preparing bricks of ice cream for consumption from the large blocks in which it is frozen, it is obvious that this device may be used for cutting a variety of relatively plastic substances, such as butter, clay and the like, and we do not limit ourselves to any particular use.

We claim:

1. A machine for cutting masses of plastic material, comprising a material-supporting base, a material-engaging element aligned along one side thereof, a plurality of cutting elements and means for drawing them horizontally across said base and into said material-engaging element and out of line with the material cut, said element being recessed to receive said cutting elements, a terminal stop adapted to engage the material to be cut and means for withdrawing said stop in unison with the cutting excursion of the cutting elements.

2. A machine for cutting masses of plastic material, comprising a material-supporting base, a material-engaging element aligned along one side thereof, a plurality of cutting elements and means for drawing them across said base and into said material-engaging element, said element being recessed to a depth sufficient to admit the entire length of said cutting elements, a terminal stop adapted to engage the material to be cut and means for withdrawing it in unison with the cutting excursion of the cutting elements.

3. A machine for cutting masses of plastic material, comprising a material-supporting base, a material-engaging element aligned along one side thereof, a plurality of cutting elements and means for drawing them across said base and into said material-engaging element, said element being recessed to receive said cutting elements, a terminal stop adapted to engage the material to be cut and means for withdrawing

it in unison with the cutting excursion of the cutting elements, comprising a pin in connection with said cutting elements and a lug on the terminal stop adapted to be engaged thereby.

4. A machine for cutting masses of plastic material, comprising a material-supporting base, a material-engaging element aligned along one side thereof, a plurality of cutting elements and means for drawing them across said base and into said material-engaging element, said element being recessed to a depth sufficient to admit the entire length of said cutting elements, a terminal stop adapted to engage the material to be cut and means for withdrawing it in unison with the cutting excursion of the cutting elements, comprising a pin in connection with said cutting elements and a lug on the terminal stop adapted to be engaged thereby.

5. A machine for cutting masses of plastic material, comprising a material-supporting base, a material-engaging element aligned along one side thereof, a plurality of cutting elements and means for drawing them across said base and into said material-engaging element, said element being recessed to receive said cutting elements, a terminal stop adapted to engage the material to be cut and means for withdrawing it in unison with the cutting excursion of the cutting elements, comprising a pin in connection with said cutting elements and a lug on the terminal stop adapted to be engaged thereby, and automatic means for returning the terminal stop to position when the cutting elements are withdrawn.

6. A machine for cutting masses of plastic material, comprising a material-supporting base, a material-engaging element aligned along one side thereof, a plurality of cutting elements and means for drawing them across said base and into said material-engaging element, said element being recessed to a depth sufficient to admit the entire length of said cutting elements, a terminal stop adapted to engage the material to be cut and means for withdrawing it in unison with the cutting excursion of the cutting elements, comprising a pin in connection with said cutting elements and a lug on the terminal stop adapted to be engaged thereby, and automatic means for returning the terminal stop to position when the cutting elements are withdrawn.

7. In a machine for cutting plastic materials, a supporting base, a material-engaging element along one side thereof, a gang knife, the material-engaging element being slotted to receive the blades of the gang knife, and means for drawing the gang knife across the base and into the material-engaging element comprising a drive shaft, pinions thereon, and racks attached to the

gang knife and in engagement with the pinions.

8. In a machine for cutting plastic materials, a supporting base, a material-engaging element along one side thereof, a gang knife, the material-engaging element being slotted to receive the blades of the gang knife, and means for drawing the gang knife across the base and into the material-engaging element comprising a drive shaft, pinions thereon, and racks attached to the gang knife and in engagement with the pinions, and a terminal stop adapted to engage the material and means for withdrawing it 15 in unison with the gang knife.

9. In a gang knife for cutting ice cream, a slotted body element, said slots having vertical sides on one side and inclined sides on the opposite side, wedge blocks adapted 20 to fit in said slots, each block having a vertical side in opposition to the vertical side of the slot and an inclined side in opposition to the inclined side of the slot, knife elements adapted to be inserted between the 25 opposed vertical sides, and means for drawing said wedge blocks into said slots to clamp said knives in position.

10. In a gang knife for cutting ice cream, a slotted body element, said slots having 30 vertical sides on one side and inclined sides on the opposite side, wedge blocks adapted to fit in said slots, each block having a vertical side in opposition to the vertical side of the slot and an inclined side in opposition 35 to the inclined side of the slot, knife elements adapted to be inserted between the opposed vertical sides, and means for drawing said wedge blocks into said slots to clamp said knives in position comprising 40 rotatable elements in screw-threaded relation with said blocks.

11. A machine for cutting masses of plastic material, comprising a supporting base, a stop along one side thereof, a stop across 45 the end thereof, a plurality of cutting elements adapted to be drawn horizontally across said base, and through said side stop and out of line with the plastic material, and means for withdrawing said end stop in 50 response to the movement of said cutting elements.

12. A machine for cutting masses of plastic material, comprising a supporting base, a stop along one side thereof, a stop across 55 the end thereof, a plurality of cutting elements adapted to be drawn across said base, and means for withdrawing said end stop in response to the movement of said cutting elements, the bottoms of said stops being 60 spaced substantially above the supporting base.

13. An ice cream cutting machine adapted to receive and cut a slab of ice cream mounted upon a movable support, comprising a 65 substantially plane surfaced base, a substan-

tially vertical, slab engaging stop along one side of said base, a plurality of spaced blades mounted above said base and means for drawing them in unison across said base, through said slab and through said stop, 70 said stop being spaced substantially above the upper surface of the supporting base, said blades terminating at a distance above the base slightly greater than the thickness of the movable slab support. 75

14. An ice cream cutting machine adapted to receive and cut a slab of ice cream mounted upon a movable support, comprising a substantially plane surfaced base, a substantially vertical, slab engaging stop along one side of said base, a plurality of spaced blades mounted above said base and means for drawing them in unison across said base, through said slab and through 80 said stop, said stop being spaced substantially above the upper surface of the supporting base, said blades terminating at a distance above the base slightly greater than the thickness of the movable slab support, a terminal stop and means for withdrawing it in response to movement of the blades. 85

15. An ice cream cutting machine comprising a fixed supporting base, a supporting element adapted to be positioned thereupon, a cream engaging stop along one side of said supporting base, a plurality of downwardly projecting, spaced blades positioned above the fixed supporting base and adapted to clear the movable supporting base, and means for drawing them in unison through the ice cream, the stop being slotted to permit their passage therethrough. 90

16. An ice cream cutting machine comprising a supporting base, a cream engaging stop along one side thereof, a plurality of downwardly projecting spaced blades positioned above the supporting base, and means for drawing them in unison through the ice cream, the stop being slotted to permit their passage therethrough, said knives terminating at a point substantially above the base of said machine. 100

110

17. An ice cream cutting machine comprising a fixed supporting base, a supporting element adapted to be positioned thereupon, a cream engaging stop along one side of said supporting base, a plurality of downwardly projecting, spaced blades positioned above the fixed supporting base and adapted to clear the movable supporting base, and means for drawing them in unison through the ice cream, the stop being slotted to permit their passage therethrough, the height of the stop above the fixed base being sufficient to permit the movable base to be inserted therebeneath. 115
